United States Patent Office

Des. 179,734
Patented Feb. 19, 1957

179,734

ELECTRIC SHAVER

Harper Landell, Ambler, Pa., assignor to Schick Incorporated, Lancaster, Pa., a corporation of Delaware

Application June 26, 1956, Serial No. 42,051

Term of patent 14 years

(Cl. D22—3)

Fig. 1 is a front elevation of an electric shaver showing my new design;

Fig. 2 is a side elevation;

Fig. 3 is a rear elevation;

Fig. 4 is a top plan view; and

Fig. 5 is a bottom plan view thereof.

I claim:

The ornamental design for an electric shaver, substantially as shown.
